UNITED STATES PATENT OFFICE.

FERNANDO PEREZ, OF ADRA, SPAIN, ASSIGNOR, BY DIRECT AND MESNE ASSIGNMENTS,
TO SANITARY SAFETY RAZOR COMPANY, A CORPORATION OF NEW YORK.

SAFETY-RAZOR AND CORN-KNIFE.

1,012,428.

Specification of Letters Patent.

Patented Dec. 19, 1911.

Application filed January 28, 1911. Serial No. 605,181.

To all whom it may concern:

Be it known that I, FERNANDO PEREZ, a subject of the King of Spain, and a resident of Adra, in the Province of Almeria, Spain, 5 have invented a new and Improved Safety-Razor and Corn-Knife, of which the following is a full, clear, and exact description.

My invention relates to a new and improved form of combined safety razor and 10 corn knife, and an object of my invention is to provide a device of this character, which possesses all of the advantages of the safety razors now in common use, and additionally affords a means whereby the razor 15 may be readily cleaned.

A further object is to provide a razor of open-work construction, so as to prevent the accumulation of lather on the working face of the razor while shaving.

20 A still further object is to provide a razor in which the several relatively thin parts are reinforced.

With these and other objects in view, as 25 will more fully hereinafter appear, the present invention consists in certain novel details of construction and arrangement of parts hereinafter fully described, illustrated in the accompanying drawings and more particularly pointed out in the appended 30 claim.

Reference is to be had to the accompanying drawings, forming a part of this specification, in which similar characters of reference indicate corresponding parts in all 35 the figures, and in which

Figure 1 is a perspective view looking down upon my assembled razor; Fig. 2 is a side elevation of the same, the upper parts shown in section, to disclose the means for 40 assembling the different parts; Fig. 3 is a perspective view looking down upon the blade holder; Fig. 4 is a similar view of the blade; and Fig. 5 is a perspective view of the holding plate.

45 In the drawings, I have disclosed an ordinary form of a hollow razor blade handle 1, the bore 2 of which has screws 3 at its upper portion, into which fits the threaded shank 4 of a skeleton bearing plate 5, which 50 plate has radiating webs 6, and has lugs 7 projecting downwardly, which lugs project through apertures 8 and 9 in the blade 10

and blade holder 11 hereinafter described. Resting upon the flat end 12 of the handle 1 is a substantially square blade-holder 11, 55 comprising outer strips 13, the edge 14 of which is downwardly curved. The strips are united by integral intersecting radially-disposed webs 15. At the point of intersection of these webs, and centrally of the 60 blade holder, is an aperture 17 adapted to fit over the aperture 16 in the blade holder 11. The shank 4 of the plate 5 passes through the alined apertures 16 and 17, and screws down into the threaded end of the 65 handle to firmly bind the blade and blade holder to the handle, with the lugs 7 passing through the apertures 8 and 9. As the webs 6, 15 and 18 on the several members are similarly constructed and are super- 70 posed in juxtaposition, a series of openings 19 will extend between the same and clear through the blade and blade holder, thereby preventing the accumulation of lather on the face of the blade while shaving, and 75 facilitating the cleaning of the different parts either separately or in assembled position. The beveled or rounded portion 14 of the guard 11 has longitudinally-extending slots 20 adjacent to and parallel with 80 the outer edges and extending almost to the adjacent ends of the guard. The blade 10 is so positioned that the cutting edge 21 is substantially in line with the longitudinal center of the slot 20, and is held against vibration by the top plate 5 which conforms 85 in configuration to the blade 10 and blade holder 11.

Many changes could be made in the above construction and many apparently widely 90 different embodiments of this invention could be made without departing from the scope thereof. It is intended that all matters contained herein in the above description or shown in the accompanying drawings shall be interpreted as illustrative and not in a limiting sense. It is also to be understood that the language used in the following claim is merely intended to cover all the generic and specific features of the invention herein described, and all statements of the scope of the invention, which, as a matter of language, might be said to fall therebetween, and that materials, sizes and 95 100

relativities of parts are non-essential, except as called for in the claim.

Having thus described my invention, I claim as new and desire to secure by Letters 5 Patent:

In a safety razor, four strips integrally united, forming a rectangular blade support, diametrically intersecting ribs integral with said strips, and a similarly shaped

blade positioned on said support with the 10 ribs superposed.

In testimony whereof I have signed my name to this specification in the presence of two subscribing witnesses.

FERNANDO PEREZ.
